DESIGN FOR A NECKTIE OR SIMILAR ARTICLE

Maurice Urdang, New York, N. Y.

Application May 21, 1943, Serial No. 110,253

Term of patent 3½ years

To all whom it may concern:

Be it known that Maurice Urdang, a citizen of Lithuania but having declared his intention of becoming a citizen of the United States, and resident of the Borough of Manhattan, county of New York, city and State of New York, has invented a new, original, and ornamental Design for a Necktie or Similar Article, of which the following is a specification, reference being had to the accompanying drawing, forming part

thereof, in which the figure is a view of a folded four-in-hand necktie embodying my new design. The necktie is of the conventional type and the dominant feature of the design is the surface ornamentation on the large tab as shown.

I claim:

The ornamental design for a necktie or similar article, substantially as shown and described.

MAURICE URDANG.
